UNITED STATES PATENT OFFICE

EDWARD HILDEBRANDT, OF TACOMA, WASHINGTON

CAN AND SLIP COVER

Application filed November 2, 1928. Serial No. 316,863.

My invention relates to an improvement in cans, and has for its main object the provision of a can and cover which may be securely sealed, yet which, after opening, 5 leaves the can with a slip cover, both cover and can body being reinforced at the edges, and these edges being without rough edges or portions to catch on articles, or to cut the hands of those who handle them, or at least, 10 with the rough edges so protected that they can do no damage.

It is an object to provide a can of the character described, which may be sealed with compound, and which may be opened 15 by means of a tear-off strip, yet having the advantages as to stiffness and smoothness of the edges of both can body and cover flange referred to above.

A further object is the provision of a can 20 and cover of this general character which will be convenient and economical to manufacture.

It is a further object to provide a key for such cans which may be semi-permanently 25 associated with the tear-off strip, so that it is always in condition for use, yet carried in such a position that it does not interfere with the packing and stacking of the cans.

My invention comprises the novel construction shown in the accompanying drawings, described in the specification, and particularly defined by the claims terminating 30 the same.

In the accompanying drawings I have 35 shown my invention embodied in several forms embodying the underlying basic idea.

Figure 1 is an elevation of my improved can as it would appear ready for shipment.

The remaining figures are axial sections 40 along the line of the key tab, Figure 2 showing parts assembled but not secured together, Figure 3 showing parts secured together, Figure 4 showing parts in the relation they would occupy after the tear-off strip has 45 been removed, and Figure 5 showing the cover and can body separated after removal of the tear-off strip.

Figures 6, 7 and 8 are similar axial sections through one side of a modified form, 50 Figure 6 representing parts assembled but

not secured, Figure 7 representing them secured and with the tear-off strip removed, and Figure 8 representing the cover and can body separated.

Figure 9 is an axial section of a further 55 modification, showing parts assembled and secured together, but with the tear-off strip intact.

According to my invention, means are provided at the upper edge of the can body, or an extension thereof, which will be uppermost when the can cover is removed, these means serving to reinforce the upper edge of the final can body, and to provide a smooth edge therefor. Similarly, the 60 cover resulting after the tear-off strip has been removed is left with a reinforcing seam or bead, which also protects against any rough or sharp edges. It is immaterial whether the tear-off strip employed be 65 formed originally as a part of the can body or as a part of the flange of the cover, and both forms are shown herein. There is, of course, a seamed or like permanent securing 70 between the can cover and the can body, but it is not material whether this seam be formed above or below the tear-off strip. In effect, the tearoff strip is united at its top edge, permanently or by a seam, with the cover flange, and is united in one 75 of these ways to the can body at its lower edge.

Proceeding first to a description of the forms shown in Figures 2 to 5 inclusive, it will be noted that the cover 1 is formed with 80 a depending peripheral flange 10, and that the can body 2 has secured to its upper edge and projecting thereabove a separate collar 3. A terminal bead 4 is formed about the upper edge of the collar 3 in this instance, 85 inasmuch as this collar is in effect a portion of the body in this form, and this bead 4 therefore forms the upper edge of the can body, and reinforces this upper edge and renders it smooth. Below the upper edge 90 of the can body 2 there is formed a tear-off strip 5 provided with a tab 50 for engagement by a key 6, which key is shown only in Figure 1. To secure the several parts of 95 the can together a seam is formed at 23 be- 100

5   tween the can body 2 and the collar 3, this being located at the lower edge of the tear-off strip 5, and a bead 12 is formed between the flange 10 of the cover and the upper edge of the can body 2, this being located preferably immediately at the upper edge of the tear-off strip 5.

10   These seams 23 and 12, or the latter seam alone, in this particular form, may be filled with sealing compound, and the package may thus be made hermetically tight. Removal of the tear-off strip 5, as is indicated in Figure 4, leaves the cover 1 with its flange 10 and the seam 12 defining its lower edge, 15   free to be removed from the can body which now includes the collar 3 and its bead 4 forming its upper edge, and when this removal is effected, both the can cover and the can body are left with reinforced free edges, and 20   these edges are smooth. The remainder of the tear-off strip, which is located at the bead 12, is within and protected by the bead, and being short, is not likely to catch or to cut.

25   Whereas, in the form just described, the bead 4 was formed in a collar forming in effect an upward extension of the can body, the can body itself cooperating with and being secured to the flange of the cover, which 30   flange lies outside of this collar, it is possible to form the bead 4 in the metal of the can body itself, as is shown in Figures 6, 7, 8 and 9, and to form the tear-off strip in a separate collar 30, which may be attached 35   outside of the can body near its upper edge. Thus the collar 30 carrying the tab 50 is seamed at 23 to the can body 2, and at 12 to the can top, or rather to its depending flange 10. Sealing compound may be employed at 40   both seams, or at either one alone. Now, when the tear-off strip 5 is removed, this breaks connection between the two edges of the collar 30, one of which is retained in the bead 23, and the other in the bead 12, 45   as is best seen in Figure 7, and the cover 1 may be removed, still carrying the bead 12 as a reinforcing and protective means, and the small portion of the collar retained by the bead 23 is not liable to do any damage. 50   Further, the top edge of the can body retains the protective and stiffening bead 4. It will be noted that the seam 23 in this form is an internal seam, whereas in the previous form it was an external seam, but 55   this is immaterial.

60   The collar 3 may be omitted entirely, if desired, and such a construction is illustrated in Figure 9. In this form the flange 10 is extended downward, and the tear-off strip 5 is incorporated in this extension. A false seam 12' is formed in this flange 10 just above the upper edge of the tear-off strip 5, and the lower edge of the flange is seamed to the body 2 at 23, below the lower 65   edge of the tear-off strip 5. When the tear-

70   off strip is removed the false seam 12' still forms a stiffening reinforcement at the lower edge of the can cover flange, also protecting against a sharp edge, and the bead 4, as before, stiffens the upper edge of the can body itself.

75   While the usual keys may be employed in association with such a can, I prefer that a key be employed such as that shown in Figure 1. This key is provided with the usual shank 60 and head 61, and a slot 62 extends from the shank into the head. Through this slot 62 is passed the tab 50, and the key may be slid lengthwise of itself on this tab. Normally it may be kept in the lowered position, as shown in full lines in Figure 1, and when it is desired to tear off the strip 5 the key may be slid to the dotted line position of Figure 1, where it is immediately ready for use. This is done without any detachment of the key and subsequent attachment to the tab, and it is thus unnecessary to anchor the key in any permanent manner to the can.

80   What I claim as my invention is:

85   1. In combination with a can body and a downwardly flanged cover fitting thereon, said body terminating at its upper edge in a stiffening bead and said cover flange including a stiffening seam, a tearoff strip positioned immediately below the seam in the cover flange, and united both to the cover flange and to the can body, and means including a peripheral joint for securing the cover to the can body.

90   2. In combination with a can body terminating in a bead at its upper edge and a downwardly flanged cover fitting on said can body to produce a double thickness about its top, a tearoff strip located in the outer thickness, below the body bead, and two seams, one on either side of said tearoff strip, one seam serving to secure the cover to the can body, and one of said seams defining the lower edge of the cover when 95   said tearoff strip is removed.

100   3. In combination, a can body and a cover flanged to fit over the upper edge of the can body, a tearoff strip attached at one edge to the can body and at its other edge to the cover flange, and a seam formed in the cover flange immediately above the tearoff strip.

105   4. In combination, a can body and a cover flanged to fit over the upper edge of the can body, a tear-off strip encircling the can body below the latter's upper edge, said tearoff strip being attached at its lower edge to the can body, and at its upper edge to the cover flange, and said flange having a seam formed immediately above the upper edge of said tearoff strip.

110   5. In combination with a can body, a cover, and a collar seamed to said can body, and forming with said can body a double

thickness about its upper portion, a tear-off strip formed in the outermost thickness, below the upper edge of the combined can body and collar, a flange depending from said cover over such upper edge, and said flange being seamed to the outer thickness of material, immediately above the tear-off strip.

6. In combination with a can body, a cover, and a collar beaded at its upper edge, positioned within and seamed to said can body below, and projecting above, the latter's upper edge, a tear-off strip formed in the can body between said seam and its own upper edge, and a flange depending from said cover about the projecting, beaded upper edge of said collar, and seamed to the upper edge of the can body, adjacent but above the tear-off strip.
- 10 7. In combination with a can body and a downwardly flanged cover fitting thereon, said cover flange including a stiffening seam and being of a diameter to slip over the upper edge of the can body, a tearoff strip positioned beneath said stiffening seam, said tearoff strip being united at its upper edge to the cover flange and at its lower edge to the can body, and a strip projecting upward inside of the tearoff strip, and constituting the upper part of the can body, said latter strip terminating at its upper edge in a stiffening bead.
- 20 8. In combination with a can body and a downwardly flanged cover fitting thereon, a tearoff strip positioned below the upper edge of the can body and uniting the cover flange and the can body, below the latter's edge, an upward extension of the can body, of a diameter to slip within the cover flange, 25 above the junction of the tearoff strip therewith, when assembled lying inside of the said tearoff strip and cover flange.
- 30 40

Signed at San Francisco, California, this 26th day of October, 1928.

45 EDWARD HILDEBRANDT.
